UNITED STATES PATENT OFFICE.

GEORGE B. McBEAN AND CHARLES W. BIRCHWOOD, OF CHICAGO, ILLINOIS, ASSIGNORS
TO MECHANICAL & ELECTRICAL MANUFACTURING COMPANY, OF CHICAGO, ILLINOIS, A CORPORATION OF ILLINOIS.

CARBURETER.

1,239,611.

Specification of Letters Patent. Patented Sept. 11, 1917.

Application filed February 4, 1908. Serial No. 414,160.

To all whom it may concern:

Be it known that we, GEORGE B. McBEAN, a citizen of the United States, and a resident of Chicago, Cook county, Illinois, and
5 CHARLES W. BIRCHWOOD, a subject of the King of Great Britain, and a resident of Chicago, in the county of Cook and State Illinois, have invented certain new and useful Improvements in Carbureters, of which
10 the following is a specification.

This invention relates to carbureters.

So far as we are aware, in all carbureters now in use, the action of the motor creates a suction, which operates to draw air into
15 the carbureter and to discharge the hydrocarbon directly from the nozzle or nozzles in the form of a more or less fine spray, the air and hydrocarbon spray forming an explosive mixture which is drawn into the cylinders
20 of the motor and there exploded, all in a familiar manner.

This operation is objectionable for the reason, among others, that, owing to the form in which the hydrocarbon is delivered
25 to the carbureter, and thus to the motor, it does not become thoroughly mixed or intermingled with the air, and it almost invariably happens, therefore, that a much larger quantity of hydrocarbon is required to develop the maximum efficiency of the motor
30 than would be necessary if the hydrocarbon were delivered into the carbureter in the form of gas or vapor in a quantity sufficient to saturate the air, thus resulting in a large
35 waste of hydrocarbon.

The object of our invention, broadly stated, is to overcome this objectionable feature, by providing a carbureter in which the air entering the carbureter will become
40 saturated with hydrocarbon in gaseous or vaporized form, thus insuring proper proportions of air and hydrocarbon to produce perfect combustion and thereby developing the maximum efficiency of the motor with the
45 use of a minimum quantity of hydrocarbon.

To effect this object, our improved carbureter comprises what may be properly called a vaporizer, to which hydrocarbon is delivered by means of suitable connection
50 with a source of supply, the said vaporizer comprising an evaporating chamber or chambers equipped with means for finely attenuating or thinly drawing or spreading out the hydrocarbon delivered thereto, so

that it will be quickly and thoroughly vaporized when subjected to the suction of the motor and the action of the air current entering the carbureter. More specifically, our improved vaporizer comprises a vaporizing chamber, comprising one or more compartments provided with hydrocarbon supply passageways which communicate therewith adjacent to their lower ends and packed with a suitable porous body, preferably fine wire gauze, asbestos wool, or other incombustible material, which will exert a capillary action, which, together with the suction of the motor, will cause the hydrocarbon entering said chamber or chambers to rise therein and to spread out over, comparatively, a very large surface or area, and thus to be attenuated or thinly spread out so as to be quickly and thoroughly vaporized in the manner desired.

A further object of the invention is to provide means for positively controlling the size of the air admission opening and of the evaporating surface of the vaporizer, whereby the size of the air admission opening and the exposed evaporating surface of the vaporizer may be correspondingly varied, so as to produce a mixture containing the proper proportions of air and of hydrocarbon to effect perfect combustion.

A further object of the invention is to avoid loss of fuel, that is, hydrocarbon, when the motor is stopped by overflow from the float tank through the spray nozzles, due to lack of nicety in the adjustment and operation of the float valve which controls the delivery of hydrocarbon to the carbureter.

To effect these various objects, a carbureter of our invention comprises the various features, combinations of features and details of construction hereinafter described and claimed.

In the accompanying drawings, in which the invention is fully illustrated—

Figure 1 is a side view of a carbureter of our invention.

Fig. 2 is a plan section thereof on the line 2—2 of Fig. 1.

Fig. 3 is a vertical sectional view on the line 3—3 of Fig. 2.

Fig. 4 is a sectional view on the line 4—4 of Fig. 3.

Fig. 5 is a sectional elevation on the line 5—5 of Fig. 3; and

Fig. 6 is a top plan view of the vaporizer detached from the carbureter.

Referring now to the drawings, 1 designates the casing of the carbureter, consisting, as shown, of a hollow cylinder, the ends of which are closed by means of heads 2 and 3. To provide for access to the interior of the casing 1, the head 3 is made removable, a flange 4 thereon being screw-threaded into the end of said casing. Obviously, if for any reason considered desirable, both heads may be made removable.

The casing 1 is provided with a discharge opening 5 adapted for connection with the cylinder or cylinders of a motor by means of suitable pipe connections, not shown, and with an air admission passageway 6, formed, as shown, by a hollow downward extension 7 of said casing, said extension being open 20 at its lower end.

The vaporizer, indicated as a whole by A, comprises a chambered body portion 8, the top of which is open. Said body portion 8 of the vaporizer is positioned centrally, as 25 nearly as may be, of the air admission passageway 6, being of substantially the same shape in cross section as said air admission passageway, but smaller, thus leaving an open space on all sides thereof for the free 30 passage of air into the carbureter casing. As shown, both said air admission passageway 6 and the body portion 8 of the vaporizer are substantially rectangular in cross section, but the shape thereof is immaterial 35 and may be varied without departure from our invention.

The chamber in the body portion 8 of the vaporizer is packed with a suitable porous body 9, consisting preferably of fine wire 40 gauze, asbestos wool, or the like, which will exert a capillary action on the liquid hydrocarbon delivered into said chamber and will operate, particularly in connection with the suction of the motor, to draw the same 45 upward through said packing, so that it will become finely attenuated or thinly drawn out in condition to be quickly and thoroughly vaporized, so that the air entering said carbureter will become charged 50 or saturated therewith, thus producing a perfect explosive mixture. When wire gauze is used for forming the packing 9, the layers thereof will preferably be disposed 55 on edge parallel with the side walls of the body portion 8 of the vaporizer.

The packing 9 will also provide a resistance to the suction of the motor on any liquid or unvaporized hydrocarbon in the vaporizer, thus preventing the motor from 60 drawing any liquid hydrocarbon or an excessive quantity of vaporized hydrocarbon, that is more than is required to form a perfect explosive mixture.

As shown, the chamber in the body portion 8 of the vaporizer is divided into dif-

ferent compartments 10, 11, and 12 by partitions 13 and 14.

In the preferable construction shown, each of the compartments 10, 11 and 12 is provided with a separate hydrocarbon supply 70 passageway, which preferably opens into the bottoms of said compartments, respectively, as near the centers thereof as practicable. Preferably, also, each of said passageways is provided with independent 75 means for controlling or adjusting the size thereof, to provide for regulating the quantity of hydrocarbon delivered to said compartments, respectively.

As shown, said passageways comprise sections 15, 16 and 17, the discharge ends of which are in open communication with the compartments 10, 11 and 12, respectively, of the vaporizer, and the opposite ends of which are in open-communication with 85 chambers 18, 19 and 20 formed in a lateral extension 21 of the vaporizer A formed integral with the body portion 8 thereof, said extension 21 forming a needle valve casing, as presently explained. Said passageways 90 also comprise sections 22, 23 and 24 which connect the chambers 18, 19 and 20, respectively, with a common chamber 25 formed in the extension 21 of the vaporizer A. The sections 22, 23 and 24 of said passageway 95 are respectively controlled by needle valves 26, 27 and 28, the shanks of which are screw threaded to the ends of bores formed lengthwise in the extension 21 of the vaporizer A, which, as noted, thus forms a casing for 100 said valves. The inner ends of said needle valve bores are larger than the shanks of said needle valves at their inclosed ends and form the chambers 18, 19 and 20. The chamber 25 is connected by a pipe 29 with 105 a tank or reservoir 30 provided with a supply opening 31 in its bottom adapted to be connected to a source of hydrocarbon supply by suitable pipe connections, not shown. A desired level of hydrocarbon is adapted to be maintained in the tank or reservoir 30 and thus in the vaporizer A and its connections by means of a valve 32 controlled by means of a float 33 located in the tank 30, all in a familiar manner. As shown, the float 110 33 is so adjusted that the normal hydrocarbon level in the vaporizer will be a short distance above the bottoms of the compartments 10, 11 and 12 in the body portion 8 thereof.

Formed in the walls of the chambered body portion 8 of the vaporizer A, above the normal hydrocarbon level, are holes or openings 34, which it is found, in practice, materially increase the vaporizing action of the carbureter.

To prevent leakage around the stems of the needle valves 26, 27 and 28, the valve casing 21 extends upwardly at an angle to a point a considerable distance above the normal hydrocarbon level.

Our invention contemplates the use of any desired or approved form of throttle valve for controlling the delivery of the explosive mixture from the carbureter to the motor cylinders. Where, however, said throttle is applied at the air admission opening 6, means are also preferably provided for adjusting the evaporating surface of the vaporizer to correspond to the size of the air admission opening 6.

In the preferable construction shown, said throttle comprises connected, co-acting means for thus controlling both the discharge opening 5, the air admission opening 6, and for varying the area of the evaporating surface of the vaporizer to correspond to the size of said air admission opening. These means are as follows:—Fitted to the bore of the cylindrical casing 1 of the carbureter and mounted to rotate freely therein, is a hollow cylinder 35, said cylinder being preferably supported by means of trunnions on the ends thereof which are fitted to suitable bearings in the heads 2 and 3 of the carbureter casing 1. The valve 35 is adapted to be rotated by means of a crank arm 36 secured to the projecting end of one of the trunnions of said valve, said crank arm being connected with a suitable hand or foot lever, not shown, by a rod 37.

Formed in the valve 35 are port openings 38 and 39, of which the port 38 is of substantially the same size as the discharge opening 5 and is adapted to be brought into partial or full register therewith by rotation of said valve 35, suitable stops, not shown, operating to define the extreme positions of said valve.

The port 39 is of substantially the same shape as the air admission passageway 6 and is so located that said ports 38 and 39 will register correspondingly with the discharge opening 5 and the air admission opening 6, which they respectively control.

At what may be termed its front edge, that is, the edge thereof toward the air admission opening, when said air admission opening is closed, the port 39 is provided with a narrow forward extension 40, which is in line with the chamber 10 of the vaporizer A, being preferably centrally in line therewith, the relation being such that, when the valve 35 is in its extreme position corresponding to full closing of the discharge opening 5 and of the air admission opening 6, the forward edge of said extension 40 of said port will be substantially even with the side of the body portion 8 of the vaporizer A, which is toward said port 39. From its forward end, the sides of said extension 40 diverge from each other, gradually for a short distance and then abruptly until they merge into the adjacent side of said port 39 proper. Thus, when the valve 35 is turned to open the discharge opening 5, and

the air admission opening 6, said extension 40 of the port 39 will move across the top of the body portion 8 of the vaporizer A, uncovering, progressively and in succession the different compartments 10, 11 and 12 thereof, at first gradually and then, as the width of said extension 40 increases, more rapidly, until finally, when the air admission opening 6 and the discharge opening 5 are fully open, said vaporizer will be fully uncovered.

The vaporizer A is so located that the top or upper surface of the body portion 8 thereof will extend into close proximity to the under side of the valve 35, which will thus form a closure therefor, thus effectually preventing vaporization, excepting from the portion thereof which may be exposed through the port 39.

A sheet of wire gauze 41 secured over the top of the chamber in the body portion 8 of the vaporizer A, confines the packing 9 therein and also prevents said packing from catching on the sides of the valve 35 or the edges of the port 39.

The needle valves 26, 27 and 28 are designed, primarily, for regulating the quantity of hydrocarbon delivered to the vaporizer. By properly adjusting said valves, the size of the passages 22, 23 and 24 may be reduced until only enough hydrocarbon is delivered to the vaporizer to secure a perfect explosive mixture. In a given case, it will be necessary to determine the desired adjustment of said needle valves by actual test. Said needle valves may be secured in any desired adjustment by means of set-screws 42 threaded through the valve casing 21 in position to bear on the valve stems.

Loss of hydrocarbon by overflow from the float tank 30 due to lack of sensitiveness of the float valve, is prevented by so adjusting the float valve that the normal hydrocarbon level in the vaporizer will be a sufficient distance below the perforations 34 in the walls of the body portion 8 of the vaporizer, to insure the full closing of the valve opening 31 in the bottom of the float tank 30 before the hydrocarbon rises to the height of the lowermost of said perforations.

We claim:—

1. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, said receptacle being provided with a hydrocarbon supply passageway, and porous packing in said receptacle, suction within the carbureter casing operating to subject the contents of said receptacle to suction through the open top thereof, substantially as described.

2. In a carbureter, the combination of

7. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, said receptacle being provided with a hydro-carbon supply passageway, and porous packing in said receptacle consisting of layers of fine gauze disposed edgewise, suction within the carbureter casing operating to subject the contents of said receptacle to suction through the open top thereof, substantially as described. 75
- 10 8. In a carbureter, the combination of a casing provided with an air admission passageway and with a discharge opening, and a vaporizer, said vaporizer comprising a receptacle located in the air admission passageway, the bottom of said receptacle being closed to the air, and the top thereof open, said receptacle comprising a plurality of separate compartments each provided with an independent hydrocarbon supply passageway, and porous packing in said compartments, substantially as described. 80
- 15 9. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, said receptacle comprising a plurality of separate compartments each provided with an independent hydrocarbon supply passageway, and means for adjusting the size of said compartments, respectively, may be independently regulated, and porous packing in said compartments, substantially as described. 85
- 20 10. In a carbureter, the combination of a casing provided with an air admission passageway and with a discharge opening, and a vaporizer, said vaporizer comprising a receptacle comprising a plurality of separate compartments each provided with an independent hydrocarbon supply passageway, and means for adjusting the size of said compartments, respectively, may be independently regulated, and porous packing in said compartments, substantially as described. 90
- 25 11. In a carbureter, the combination of a casing provided with an air admission passageway and with a discharge opening, and a vaporizer, said vaporizer comprising a receptacle comprising a plurality of separate compartments each provided with an independent hydrocarbon supply passageway, and means for adjusting the size of said compartments, respectively, may be independently regulated, and porous packing in said compartments, substantially as described. 95
- 30 12. In a carbureter, the combination of a casing provided with an air admission passageway and with a discharge opening, and a vaporizer, said vaporizer comprising a receptacle comprising a plurality of separate compartments each provided with an independent hydrocarbon supply passageway, and means for adjusting the size of said compartments, respectively, may be independently regulated, and porous packing in said compartments, substantially as described. 100
- 35 13. In a carbureter, the combination of a casing provided with an air admission passageway and with a discharge opening, and a vaporizer, said vaporizer comprising a receptacle comprising a plurality of separate compartments each provided with an independent hydrocarbon supply passageway, and means for adjusting the size of said compartments, respectively, may be independently regulated, and porous packing in said compartments, substantially as described. 105
- 40 14. In a carbureter, the combination of a casing provided with an air admission passageway and with a discharge opening, and a vaporizer, said vaporizer comprising a receptacle comprising a plurality of separate compartments each provided with an independent hydrocarbon supply passageway, and means for adjusting the size of said compartments, respectively, may be independently regulated, and porous packing in said compartments, substantially as described. 110
- 45 15. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, said receptacle being provided with a hydrocarbon supply passageway, porous packing in said receptacle, and means for defining a desired level of hydrocarbon in said receptacle, the side walls of said receptacle being perforated above the normal hydrocarbon level therein, substantially as described. 115
- 50 16. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, said receptacle being provided with a hydrocarbon supply passageway, porous packing in said receptacle, and means for varying the exposed area of the top of said receptacle, substantially as described. 120
- 55 17. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, said receptacle being provided with a hydrocarbon supply passageway, porous packing in said receptacle, and means for varying the exposed area of the top of said receptacle, substantially as described. 125
- 60 18. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, said receptacle comprising a plurality of separate compartments each provided with a hydrocarbon supply passageway, said compartments comprising a relatively small compartment located at one side of said receptacle, and porous packing in said compartments, substantially as described. 130
- 65

said receptacle being provided with a hydrocarbon supply passageway, porous packing in said receptacle, means for varying the size of the admission opening to said carbureter casing and of the exposed area of the top of said receptacle, substantially as described.

12. In a carbureter, the combination of a casing provided with an air admission passageway and with a discharge opening and a vaporizer, said vaporizer comprising a receptacle located in the air admission passageway, the bottom of said receptacle being closed to the air and the top thereof open, said receptacle being provided with a hydrocarbon supply passageway, porous packing in said receptacle, means for controlling the discharge opening from said carbureter casing to vary the size thereof, and means for varying the size of the exposed area of the top of said receptacle, substantially as described.

13. In a carbureter, the combination of a casing provided with an air admission passageway, and with a discharge opening, and a vaporizer, said vaporizer comprising a receptacle located in the air admission passageway, the bottom of said receptacle being closed to the air and the top thereof open, said receptacle being provided with a hydrocarbon supply passageway, porous packing in said receptacle, means for varying the size of the admission opening to said carbureter casing and of the exposed area of the top of said receptacle, and means for varying the size of the discharge opening from said carbureter casing, substantially as described.

14. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, said receptacle comprising a plurality of compartments each provided with an independent hydrocarbon supply passageway, porous packing in said compartments, means for varying the size of the admission opening to said carbureter casing, and for covering and uncovering the tops of the compartments of the vaporizer receptacle, substantially as described.

15. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, said receptacle comprising a plurality of compartments each provided with an independent hydrocarbon supply passageway, porous packing in said compartments, means

for varying the size of the admission opening to said carbureter casing, and for progressively covering and uncovering the tops of the compartments of said vaporizer receptacle in succession, substantially as described.

16. In a carbureter, the combination of a casing provided with an air admission passageway and with a discharge opening, and a vaporizer, said vaporizer comprising a receptacle located in the air admission passageway, the bottom of said receptacle being closed to the air and the top thereof open, and porous packing in said receptacle, said receptacle being provided with a hydrocarbon supply passageway and co-acting means controlling the discharge opening from said carbureter, the admission opening thereto and the exposed area of the top of the vaporizer receptacle, whereby the sizes of said discharge opening, admission opening, and the exposed area of the top of the vaporizer receptacle may be simultaneously and correspondingly varied, substantially as described.

17. In a carbureter, the combination of a casing provided with an air admission passageway formed by a hollow extension of said casing open at its end and with a discharge opening, and a vaporizer located in said air admission passageway, said vaporizer comprising a receptacle, located in the air admission passageway, the bottom of said receptacle being closed to the air and the top thereof open, said receptacle being provided with a hydrocarbon supply passageway, and porous packing in said receptacle, said carbureter casing being provided with an interior valve seat, a hollow valve mounted to rotate in said seat, said valve being provided with a port or opening adapted to be brought into and out of register with the air admission passageway to said carbureter by rotation of said valve, the position of the vaporizer receptacle within said air admission passageway being such that the open top thereof will extend into close proximity to the surface of said valve, which thus forms a closure adapted for covering and uncovering the vaporizing surface of said receptacle, substantially as described.

18. In a carbureter, the combination of a casing provided with an air admission passageway formed by a hollow extension of said casing open at its end and with a discharge opening, a vaporizer located in said air admission passageway, said vaporizer comprising a receptacle located in the air admission passageway, the bottom of said receptacle being closed to the air and the top thereof open, said receptacle being provided with a hydrocarbon supply passageway, and porous packing in said receptacle, said carbureter casing being provided with

an interior valve seat, a hollow valve mounted to rotate in said seat, said valve being provided with a port or opening adapted to be brought into and out of register with the 5 air admission passageway to said carbureter by rotation of said valve, the position of the vaporizer receptacle within said air admission passageway being such that the open top thereof will extend into close proximity to the surface of said valve, which thus forms a closure adapted for covering and uncovering the vaporizing surface of said receptacle, said port or opening comprising a narrow extension at the side thereof to 10 ward the vaporizer when said port is closed, substantially as described.

19. In a carbureter, the combination of a casing provided with an air admission passageway formed by a hollow extension of
20 said casing open at its end and with a discharge opening, a vaporizer located in said air admission passageway, said vaporizer comprising a receptacle located in the air admission passageway, the bottom of said
25 receptacle being closed to the air and the top thereof open, said receptacle being provided with a hydrocarbon supply passageway, and porous packing in said receptacle, said carbureter casing being provided with
30 an interior valve seat, a hollow valve mounted to rotate in said seat, said valve being provided with a port or opening adapted to be brought into and out of register with the air admission passageway to said carbureter
35 by rotation of said valve, the position of the vaporizer receptacle within said air admission passageway being such that the open top thereof will extend into close proximity to the surface of said valve, which thus
40 forms a closure adapted for covering and uncovering the vaporizing surface of said receptacle, said port or opening comprising a narrow extension at the side thereof toward the vaporizer when said port is closed,
45 the sides of which diverge from its forward end, substantially as described.

20. In a carbureter the combination of a casing provided with an air admission passageway formed by a hollow extension of the carbureter casing open at its end, a discharge opening, and a vaporizer, said vaporizer comprising a receptacle positioned in said air admission passageway, said receptacle comprising a plurality of separate compartments, the bottoms of said compartments being closed to the air and the tops thereof open and each of said compartments being provided with an independent hydrocarbon supply passageway, and porous packing in said compartments, said carbureter casing being provided with a valve seat, a hollow valve mounted to rotate in said seat, said valve being provided with a port or opening adapted to be brought into and out of register with the air admission passageway.

way to said casing by rotation of said valve, the position of the vaporizer receptacle within the air admission passageway being such that the tops of the compartments thereof will extend into close proximity to the surface of said valve, which will thus form a closure adapted for covering and uncovering the compartments of said receptacle in succession as said valve is rotated, substantially as described. 70 75

21. In a carbureter, the combination of a casing provided with an air admission passageway formed by a hollow extension of the carbureter casing open at its end, a discharge opening, and a vaporizer, said vaporizer comprising a receptacle positioned in said air admission passageway, said receptacle comprising a plurality of separate compartments, the bottoms of said compartments being closed to the air and the tops thereof open and each of said compartments being provided with an independent hydrocarbon supply passageway, and porous packing in said compartments, said carbureter casing being provided with a valve seat, a hollow valve mounted to rotate in said seat, said valve being provided with a port or opening adapted to be brought into and out of register with the air admission passageway to said casing by rotation of said valve, the position of the vaporizer receptacle within the air admission passageway being such that the tops of the compartments thereof will extend into close proximity to the surface of said valve, which will thus form a closure adapted for covering and uncovering the compartments of said receptacle in succession as said valve is rotated, said port or opening comprising a narrow extension at its side which is toward the vaporizer receptacle when said port is closed, substantially as described. 80 85 90 95 100 105

22. In a carbureter, the combination of a casing provided with an air admission passageway formed by a hollow extension of the carbureter casing open at its end, a discharge opening, and a vaporizer, said vaporizer comprising a receptacle positioned in said air admission passageway, said receptacle comprising a plurality of separate compartments, the bottoms of said compartments being closed to the air and the tops thereof open and each of said compartments being provided with an independent hydrocarbon supply passageway, and porous packing in said compartments, said carbureter casing being provided with a valve seat, a hollow valve mounted to rotate therewith, said valve being provided with a port or opening adapted to be brought into and out of register with the air admission passageway to said carbureter by rotation of said valve, the position of the vaporizer receptacle within said air admission passageway being such that the tops of the compartments 130

- thereof will extend into close proximity to the surface of said valve which will thus form a closure adapted for progressively uncovering the same in succession as said valve 5 is rotated, the relatively small compartment of said vaporizing chamber being located at the side of the vaporizer toward said port when said port is closed and said port comprising a narrow extension in line with said 10 relatively small compartment of the vaporizing receptacle, substantially as described.
23. A vaporizer comprising a receptacle, the bottom of said receptacle being closed to the air and the top thereof open, said receptacle being provided with a hydrocarbon supply passageway, and porous packing in 15 said receptacle, whereby suction applied to said vaporizer will operate to subject the contents of said vaporizer receptacle to suction through the open top thereof, substantially as described.
24. A vaporizer comprising a receptacle comprising a plurality of separate compartments, the bottoms of which are closed to 25 the air and the tops thereof open, each of said compartments being provided with an independent supply passageway, and porous packing in said compartments, whereby suction applied to said vaporizer will operate 30 to subject the contents of said vaporizer receptacle to suction through the open top thereof, substantially as described.
25. A vaporizer comprising a receptacle, comprising a plurality of separate compartments, the bottoms of which are closed to the 35 air and the tops thereof open, each of said compartments being provided with an in-
- dependent hydrocarbon supply passageway, and means for adjusting the sizes of said hydrocarbon supply passageways, whereby 40 the quantity of hydrocarbon delivered to said compartments, respectively, may be independently regulated, and porous packing in said compartments, substantially as described. 45
26. A vaporizer comprising a receptacle, comprising a plurality of separate compartments the bottoms of which are closed to the air and the tops thereof open, said compartments being provided with hydrocarbon supply 50 passageways, said compartments comprising a relatively small compartment located at one side of said receptacle, and porous packing in said compartments, substantially as described. 55
27. A vaporizer comprising a receptacle, the bottom of said receptacle being closed to the air and the top thereof open, and said receptacle being provided with a hydrocarbon supply passageway, porous packing in 60 said receptacle, and means for defining a desired level of hydrocarbon in said receptacle, the side walls of said receptacle being perforated above the desired hydrocarbon level therein, substantially as described. 65

In testimony that we claim the foregoing as our invention, we affix our signatures in presence of two subscribing witnesses, this 30th day of January, A. D. 1908.
